UNITED STATES PATENT OFFICE.

MAX L. HILLMER, OF DETROIT, MICHIGAN, ASSIGNOR TO THE REMY ELECTRIC COMPANY, A CORPORATION OF INDIANA.

COVER AND COVER-SECURING MEANS.

Application filed October 30, 1918. Serial No. 260,243.

To all whom it may concern:

Be it known that I, MAX L. HILLMER, a citizen of the United States of America, residing at Detroit, county of Wayne, State of Michigan, have invented certain new and useful Improvements in Cover and Cover-Securing Means, of which the following is a full, clear, and exact description.

This invention relates to covers and cover securing means for apparatus, as such for example, ignition coils for automobiles, which when in use are subjected to jarring and vibration; and to devices for securing the covers in position in such a manner that they cannot become loose during jarring or vibration, said devices permitting the removal of the cover when desired.

The chief object of this invention is to provide improved means for securing the covers of an apparatus in position in the manner referred to, that is, so that the covers will be held in position in a thoroughly reliable manner, but so that the covers can be readily removed when desired.

Other and further objects of this invention will be apparent from the following description, reference being had to the accompanying drawings, wherein a preferred embodiment of the present invention is clearly shown.

Referring to the drawings:

Fig. 1 is a side elevation of an ignition coil to which the present invention is applied, the cover being shown in section for sake of clearness;

Fig. 2 is a plan view of the cover shown in Fig. 1;

Fig. 3 is a fragmentary section on the line 3—3 of Fig. 2;

Fig. 4 is a side elevation of the nut forming part of the securing device;

Fig. 5 is a bottom plan view thereof; and

Fig. 6 is view of a modified form of the invention.

Referring to the drawings, 20 indicate as a whole an ignition coil which may comprise a cylindrical portion 21, a bottom 22 and a top 23 serving as a cover support, within which the windings and condenser of the coil may be enclosed. A rod 24 having threaded engagement at its lower end with

the bottom 22 extends upwardly through the top 23 and has at its upper end a threaded portion 25. A nut 26 cooperates with the threaded portion 25 and serves to secure the parts 21, 22 and 23 in position, in order to form a hollow compartment for certain parts of the ignition coil. The ignition coil resistance element 27 is mounted upon the top 23. The ignition coil may have a number of terminals which are mounted upon the cover 23, one of these terminals being shown at 28.

It may be desirable to cover or to enclose the resistance element and the terminals, in order to protect them from dust and dirt or grease, particularly where the ignition coil is used on an automobile. In order to provide such an enclosure I provide a cover 30 which cooperates with the top member 23 to form an enclosure for the resistance element 27 and the terminal 28. In order to provide a means for securing the cover in position upon the top member 23 of the ignition coil, I take advantage of the presence of the rod 24, and extend the rod 70 beyond the nut 26 so that the rod 24 may pass through an aperture 31 formed in the cover 30. The nut 32 cooperates with the threaded portion 25 of the rod 24 to secure the cover 30 in position as shown in 80 Fig. 1.

It is usually the practice to provide the nut with a lock washer in order to prevent the nut from turning due to jarring or vibration. But in the present invention I 85 have eliminated the lock washer and have provided cooperating portions or surfaces on the cover and the nut in order to prevent the nut from turning, except where it is desired to remove the cover.

The cooperating portions referred to consist of grooves 33 formed on the under surface of the nut as shown more clearly in Figs. 4 and 5; and ridges 34 are provided in the cover by extruding the metal of the cover 95 in the manner shown in Fig. 3. These ridges 34 bear the same relation to the aperture 31 as the grooves 33 bear to the tapped hole in the nut 32.

It is apparent therefore that in order to 100 secure the cover in position it is necessary only, first to place the cover upon the top 23

with the rod 24 extending through the aperture 31 of the cover, and then to place the nut 32 on the threaded portion 25 with the grooved surface and adjacent the cover. 5 The nut is then screwed downwardly until the lower surface thereof contacts with the ridges 34. The nut is screwed down further on the rod 24 causing the cover 30 to flex downwardly as viewed in Fig. 1, but when the 10 grooves 33 and the nut 32 come opposite the ridges 34, the ridges 34 will spring upwardly as viewed in Fig. 1, into engagement with the grooves 33 thus locking the nut in position. The more the nut is screwed 15 downwardly on the rod 24 the more firm will be the locking engagement between the ridges 34 and the grooves 33. Thus it will be seen that the lock washer which is usually employed has been eliminated. I have taken 20 advantage of the flexibility of the cover as a means which will yieldingly but securely hold the nut in position and keep it from turning when the coil is being subjected to jarring or vibration. Now when it is desired to remove the cover it is only necessary 25 to apply a wrench or similar device to the nut to remove the same from the rod 25. When this has been done the cover can be removed simply by lifting it away from the 30 coil 20.

If desired, the cover may be provided with the depressions 33, and the nut may be provided with the ridges 34.

Where the rod 24 is not long enough to 35 extend through the cover, the nut 40 shown in Fig. 6 may be used. This nut 40 has a shank portion 41 which extends through the aperture 34 in cover 30, and is provided with a tapped hole 42 which is engaged by 40 the screw-threaded end 25 of the rod 24. The nut 40 is provided with grooves 43 which cooperate with the ridges 34 in the manner described in connection with the first form of the invention. A split ring 44 45 cooperates with a groove on the shank 41 to prevent accidental withdrawal of the nut from the cover.

By referring to Fig. 1, it will be noted that the cover 30 and supporting member 23 50 have annular co-operating surfaces, whereby, when pressure is applied by the locking nut, the cover will be prevented from turning with respect to the member 23 by virtue of the frictional force between these co-operating surfaces.

While the cover and securing device has been shown in connection with ignition coil it is to be understood that the invention could be applied to other forms of apparatus.

60 While the form of mechanism herein shown and described constitutes a preferred form of embodiment of the invention, it is to be understood that other forms might be adopted, all coming within the scope of the claims which follow.

1. In a device of the kind described, the combination with a support and a flexible cover therefor; of a fixed member secured to the support; and movable means cooperating with the fixed member to secure the 70 cover in position upon the support, said cover and movable means having cooperating portions, the cover portions adapted by the flexing of the cover to spring into interlocking relation with said portions of said 75 movable means in order to prevent the moving of said movable means due to the jarring or vibration of the support and cover.

2. In a device of the kind described, the combination with a support and a flexible 80 cover therefor; of a threaded rod secured to the support and a nut on the rod and cooperating with the cover to secure the same in position upon the support, said nut and cover having portions, the cover portions 85 adapted by the flexing of the cover to spring into interlocking relation with said nut portions to secure the nut in fixed position upon the cover.

3. In a device of the kind described, the combination with a support and a flexible cover therefor; of a threaded rod secured to the support and extending through the cover; and a nut provided with grooves 90 cooperating with the rod and the cover to secure the cover in position upon the support, said cover being provided with ridges 95 adapted by the flexing of the cover to spring into cooperation with the grooves of the nut whereby yieldingly to hold the nut in position.

4. In a device of the kind described, the combination with a support and a flexible cover therefor; of a threaded rod secured to the support; and a nut having an internally 105 threaded shank extending through a hole in the cover, said nut and cover being provided with portions, the cover portions adapted by the flexing of the cover to spring into interlocking relation with the nut portions to secure the nut in fixed position in relation to the cover.

5. In a device of the kind described, the combination with a support and a flexible 110 cover therefor; of a threaded rod secured to the support; and a nut having an internally threaded shank extending through a hole in the cover, and having grooves provided in a surface thereof adjacent a surface of the cover; said cover being provided with ridges 115 adapted by the flexing of the cover to spring into cooperation with the grooves of the nut whereby yieldingly to lock the nut in fixed position in relation to the cover.

6. In a device of the kind described, the combination with a support and a flexible cover therefor; of a threaded rod secured to the support; and a nut having an internally 120 threaded shank extending through a hole in the cover, and having grooves provided in 125

a surface thereof adjacent a surface of the cover; said cover being provided with ridges adapted by the flexing of the cover to spring into cooperation with the grooves of the nut whereby yieldingly to lock the nut in fixed position in relation to the cover; and means for preventing withdrawal of the nut from the cover.

7. In a device of the kind described, the combination with a support and a flexible cover therefor; of a threaded rod secured to the support; and a nut having an internally threaded shank extending through a hole in the cover, and having grooves provided in a surface thereof adjacent a surface of the

cover; said cover being provided with ridges adapted by the flexing of the cover to spring into cooperation with the grooves of the nut whereby yieldingly to lock the nut in fixed position in relation to the cover; and means for preventing withdrawal of the nut from the cover, said means comprising a split spring ring cooperating with a groove provided in the shank of said nut.

In testimony whereof I affix my signature. 23

MAX L. HILLMER.
